UNITED STATES PATENT OFFICE.

ALFRED FRANTZ AND PAUL FRANQUET, OF MILTON, PENNSYLVANIA.

RAIL-FASTENING.

1,032,280.

Specification of Letters Patent.

Patented July 9, 1912.

Application filed April 13, 1911. Serial No. 620,844.

To all whom it may concern:

Be it known that we, ALFRED FRANTZ and PAUL FRANQUET, citizens of the United States, residing at Milton, in the county of Northumberland and State of Pennsylvania, have invented certain new and useful Improvements in Rail-Fastenings, of which the following is a specification.

Our invention relates to an improvement in rail fastenings, and the object is to provide means whereby the rail will be firmly held upon the tie by means of clamping blocks which are forced against the base flange of the rail, and held in such position by means of wedges. As the block is forced upon the base flange of a rail, the block will tend to rise, and the rear end to come in closer engagement with the wedge.

A further object is in the provision of a link plate which engages the tie and is connected to the wedge for locking the wedge against movement.

The invention consists in certain novel features of construction and combinations of parts which will be hereinafter fully described and pointed out in the claims.

In the accompanying drawings:—Figure 1 is a top plan view of the invention, Fig. 2 is a longitudinal vertical sectional view, Fig. 3 is a top plan view of the clamping block and wedge, and Fig. 4 is a cross sectional view through the tie and the clamping block.

A, represents a metallic tie, which is closed preferably at its ends, and is made hollow. A rail B is mounted upon the upper surface of the tie, and on each side of the rail, openings 1, 1, are formed, in which the clamping block is received. The clamping block is provided with a base 2, and mounted upon the base is a dog 3 which engages the base flange of the rail. The base of the clamping block extends outwardly on each side of the clamping dog, and enters grooves or runways 3', formed in the tie, while the dog 3 passes through the longitudinal slot 4, formed in the upper surface of the tie leading from the opening 1. A wedge 5 passes through the tie, and is provided with a tapering or beveled edge 6, which engages the tapering or beveled edge 7 of the base 2 of the clamping block. The dog 3 projects rearwardly over and upon the wedge 5, so that as the clamping block is forced through the slot 4 on to the base flange of the rail, by driving the wedge through the tie, the

forward end of the dog 3 will be engaging the inclined surface of the base flange of the rail B, causing the rear end of the dog to bite or engage the wedge 5, producing a locking engagement for securely holding the rail upon the tie, and thereby avoiding any possibility of the rail rising from the tie due to the vibrations of the rail incident to the passing of a train or engine over the rail. To insure the holding of the wedge in position, I have provided a link or slotted plate 8 which is mounted upon the wedge, and is fastened thereto by means of a screw-bolt 9, which is preferably made with five sides, whereby the nut must be turned by a special wrench. One end of the plate is brought against one edge of the tie, and preferably against the edge of the tie, toward the enlarged end of the wedge 5. In this way, it is impossible for the wedge to move or become disengaged from the tie, thereby insuring the clamping block being held in position at all times. It is to be noticed that the wedge, plate, and bolt are located below the upper surface of the tie, so that in case of the derailment of an engine or train, these parts will not be affected.

It is our intention that the clamping block should be located upon each side of the rail, which is capable of movement longitudinally of the tie, whereby the rail can be adjusted for obtaining the proper alinement. In many instances, the rails get out of alinement, and it is necessary to re-align. With this device, the wedges 5 can easily be loosened and the rails shifted either in an inward or outward direction to obtain the proper alinement, when the wedges can then be fastened or moved against the clamping blocks for fastening the rail in position.

With this invention, either or both rails can be adjusted longitudinally of the tie for keeping the track in its proper alinement by simply releasing the wedges and link plate and moving the clamping blocks away from the flanges of the rail through the guide-ways sufficiently to allow the rails to be shifted. Furthermore with a tie and fastening of this character, the rail, when worn or broken, can be removed and a new rail substituted readily; and further the objection of the rising of the spikes due to the vibration of a rail, is entirely overcome by this invention, as no spikes are employed.

in holding the rail to the tie. The clamping blocks, when once put in place, cannot become removed, and therefore the rail must be rigidly held to the tie.

5 Having fully described our invention, what we claim as new and desire to secure by Letters Patent, is:—

1. In a rail fastening, the combination with a tie having openings therein, of 10 clamping blocks slidably mounted in the tie, wedges for fastening the blocks against the rail for fastening the rail to the tie, a slotted plate mounted on each wedge, having one end thereof engaging an edge of the 15 tie, and means for fastening the plate to the wedge for preventing any movement of the wedge.

2. In a rail fastening, the combination with a tie having openings therein, and 20 grooves formed in the inner side of the tie, of clamping blocks comprising bases and dogs, the base of each dog being received in the openings of the tie and received in the grooves, wedges for forcing the blocks 25 through the grooves for causing the dogs to engage the rail for fastening a rail upon the tie, and slotted plates mounted upon the

wedges, one end of the plates engaging the inner edge of the tie, and means for fastening the plates to the wedges for locking the 30 wedges against movement.

3. In a rail fastening, the combination with a tie having openings therein, and 35 grooves formed in the inner side of the tie, of clamping blocks comprising bases and dogs, the base of each dog being received in the openings of the tie and received in the grooves, wedges for forcing the blocks through the grooves for causing the dogs to engage the rail for fastening a rail upon 40 the tie, and slotted plates mounted upon the wedges beneath the upper surface of the tie, one end of the plates engaging the inner edge of the tie, and means for fastening the plates to the wedges for locking the 45 wedges against movement.

In testimony whereof we affix our signatures in the presence of two witnesses.

ALFRED FRANTZ.
PAUL FRANQUET.
